UNITED STATES PATENT OFFICE.

WARREN J. SUTLIFF, OF SCHENECTADY, NEW YORK.

JOURNAL-BOX.

1,126,126.

Specification of Letters Patent. Patented Jan. 26, 1915.

Application filed April 13, 1914. Serial No. 831,521.

To all whom it may concern:

Be it known that I, WARREN J. SUTLIFF, a citizen of the United States of America, residing at Schenectady, in the county of Schenectady and State of New York, have invented certain new and useful Improvements in Journal-Boxes, of which the following is a specification.

The present invention relates to improvements in journal boxes, and is applied especially to the cellar of the driving box of a locomotive of the steam railroad type.

The object of the invention is to improve the construction of the cellar in relation to its driving box so that certain difficulties may be overcome, and objectionable features eliminated in the driving box construction of railroad locomotives in modern use.

The invention consists essentially in a sectional cellar and means for holding the sections together, so that in use, where the space between two boxes is less than the length of the box and consequently difficulty is encountered in placing the cellar, the cellar may be placed in position in sections, and when once located the parts are firmly held together.

In the accompanying drawings I have illustrated one complete example of the physical embodiment of my invention constructed according to the best mode I have so far devised for the practical application of the principles of the invention, and a modified form of the invention is also illustrated.

Figure 1 is a front elevation of a journal box embodying the present invention, showing the journal in section. Fig. 2 is a longitudinal, sectional view of the cellar. Fig. 3 is a sectional view of the front section of the cellar. Fig. 4 is a similar view of the rear section. Fig. 5 is an edge view of the base plate or bottom of the cellar. Fig. 6 is a side elevation of a modified form of cellar, the base plate being omitted.

In the form of the invention illustrated in Figs. 1 to 5, the cellar is adapted for use with grease as a lubricant. The box 1, journal bearing or brass 2 and journal 3 are of usual type, and the box is fitted with a pair of studs 4, 4 projecting from the front wall thereof near the bottom. These studs are tapped into holes in the box and are provided with suitable locking means to hold the perforated key 6 which is located in position between the longitudinally extending

ribs 7, 7 on the front of the front section 8 of the cellar. The rear section of the cellar is indicated broadly by the numeral 9, and it will be seen that these two sections 8 and 9, when placed together in the box, as in Fig. 2, occupy the same space and position as the usual cellar.

When grease is used as a lubricant a bottom to the cellar sections is unnecessary, and thus the front section 8 comprises the side walls 10, front wall 11 and a back wall 12, having an opening 13 cut therein. The wall (or partition as it becomes when the sections are placed together) extends across from side to side of the front section, and the opening 13 also extends the entire width of the cellar, or in other words the portion marked 12 in Fig. 3 is merely a cross bar extending from side to side of the section at its rear.

The rear section 9 of the cellar is open at the front except for a cross bar 14 extending from the sides 15 of the section, and as will be immediately apparent, this bar 14 is adapted to fit into the opening 13 in the front section. The rear wall 16 of the rear section 9 has the curved upper face or edge as has the front wall 11, but at the lower outer edge of the wall 16 an angular groove 17 is formed extending from side to side of the rear section. This groove is adapted to receive and accommodate a rib 18 projected above the surface of the base plate 19, and located at the rear extremity thereof. The base plate forms the bottom of the cellar, and the two sections of the cellar are secured to the plate by means of the rib and groove connection at the rear, and also at the front by a bolt 20 passed through complementary lugs 21 22 integral with the front section 8 and the base plate respectively. The relationship of the three sections of the cellar is clearly illustrated in Fig. 2, wherein the front and rear sections of the cellar are rigidly and permanently held together by the described connections.

At the two sides of the base plate 19 a groove 19' is formed on which the sections rest and this groove prevents lateral displacement of the cellar. The back wall of the front section and the front wall of the rear section form an intermediate partition for the cellar, and an additional surface for the journal bearing, and, as usual the grease for lubrication is contained in the cellar at both sides of the intermediate partition.

In Fig. 6 a side elevation of a sectional cellar is shown that is adapted for use with the same base plate, but this cellar has a bottom of its own and is adapted to contain oil as a lubricant. The intermediate partition in this instance is formed by the rear wall 23 of the front section 8' and the front wall 24 of the rear section 9'.

The usual locking keys 25, 25, are employed to lock the cellar in the box.

From this description taken in connection with the drawings it is evident that I have provided a device which may be attached or detached with facility, even though the space be insufficient to manipulate the cellar as a whole. For instance, when taking out the cellar, with the bolt 20 and the key 6 removed, the front section may be first dislodged, and then the rear section 9 may be easily withdrawn. If necessary, when locating the parts of the cellar, the reverse of this procedure may be adopted, and the cellar placed in position in sections and then firmly held by the base plate and its connection to the box.

Having thus fully described my invention, what I claim is:—

1. In a journal box, a cellar comprising a base plate, a front and a rear section, and means for securing these sections together. 30

2. A cellar comprising a front and rear section and a base plate, the front section having a rear cross bar and the rear section having a front cross bar interlocked together to hold the sections in place. 35

3. A cellar comprising a front section with a rear cross bar and a rear section with a front cross bar locked together, and a base plate joining the sections.

4. The combination in a cellar comprising a front section and a rear section with interlocking parts, of a base plate having a rib thereon engaging a groove in the rear section of the cellar. 40

In testimony whereof I affix my signature 45 in presence of two witnesses.

WARREN J. SUTLIFF.
